Primary Examiner — John Windmuller(74) *Attorney, Agent, or Firm* — Knobbe Martens Olson & Bear, LLP**CLAIM**

The ornamental design for an umbrella runner, as shown and described.

DESCRIPTION

FIG. 1 is a perspective view of an umbrella runner showing my new design;

FIG. 2 is a front elevation view thereof, the rear elevation view being identical;

FIG. 3 is a right side elevation view thereof, the left side elevation view being identical;

FIG. 4 is a top plan view thereof;

FIG. 5 is a bottom plan view thereof; and,

FIG. 6 is a perspective view thereof in use with an umbrella. The broken lines in FIGS. 1 through 5 depict portions of the umbrella runner that form no part of the claimed design. The broken lines in FIG. 6 depict environment only and form no part of the claimed design.
